(57) **CLAIM**

The ornamental design for a trimmer line blade, as shown and described.

DESCRIPTION

FIG. 1 is a perspective view of the first embodiment of a trimmer line blade;

FIG. 2 is a front view thereof;

FIG. 3 is a side view thereof;

FIG. 4 is a cross-section view taken through line 4-4 in FIG. 2;

FIG. 5 is a perspective view of the second embodiment of a trimmer line blade;

FIG. 6 is a front view thereof;

FIG. 7 is a side view thereof; and,

FIG. 8 is a cross-section view taken through line 8-8 in FIG. 6.

The broken lines shown in the figures represent portions of a trimmer line blade that form no part of the claimed design.
